RAZOR BLADE SHARPENER

James Percival Ross, Girvin, Saskatchewan,
Canada

Application December 29, 1943, Serial No. 516,098

2 Claims. (Cl. 51—153)

The present invention relates to new and useful improvements in safety razor blade sharpeners of the type comprising a stationary strop and a traveling, oscillating holder cooperable therewith.

An important object of the invention is to provide, in a manner as hereinafter set forth, a sharpener of the aforementioned character comprising unique means for actuating the holder and for regulating the pressure of the blade on the strop.

Another important object of the invention is to provide a sharpener of the character described which embodies a novel construction and arrangement whereby the tension of the strop may be regulated as desired.

Still another very important object of the invention is to provide a safety razor blade sharpener which is provided with means whereby the blade may first be conveniently honed, if desired.

Other objects of the invention are to provide a safety razor blade sharpener of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a safety razor blade sharpener constructed in accordance with the present invention.

Figure 2 is a top plan view of the device, showing the combination carriage and shield in horizontal section.

Figure 3 is a view in vertical longitudinal section through the device.

Figures 4, 5 and 6 are cross sectional views, taken substantially on the lines 4—4, 5—5 and 6—6, respectively, of Figure 2.

Figure 7 is a fragmentary view in horizontal section, taken substantially on the line 7—7 of Figure 1, showing the belt adjusting means.

Figure 8 is a top plan view of the blade holder with the removable clamp omitted.

Referring now to the drawings in detail, it will be seen that the embodiment of the invention which has been illustrated comprises an elongated base of substantially channel-shaped cross section which is designated generally by reference numeral 1, said base being of any suitable dimen-

sions and material. The base 1, which is open at its ends, comprises a bottom 2 and upstanding side walls 3. The side walls 3 are provided, on their upper edges, with integral, inturned guide flanges 4 of angular cross section, the purpose of which will be presently set forth.

Mounted longitudinally under tension in the lower portion of the base 1 and spaced from the bottom 2 thereof is a strop 5. One end of the strop 5 has firmly secured thereon a plate 6. A screw 7, rotatably mounted on a bracket 8 on the bottom 2 of the base 1, is threadedly connected to the plate 6 for adjusting or regulating the tension of the suspended strop 5.

15 Mounted for reciprocation in the base 1 is a manually operable carriage of substantially inverted U shape which is designated generally by reference character 9. The legs 10 of the carriage 9 terminate, at their lower ends, in outwardly turned feet 11 which are slidable on the bottom 2 of the base 1. These legs 10 are slideable between the depending portions of the flanges 4. The top or right portion of the carriage 9 is arcuate to provide a hone 12 and has secured therein a suitable abrasive sheet 13.

20 Journaled for oscillation between the lower portions of the carriage legs 10, above the strop 5, is a shaft 14. One end portion of the shaft 14 projects beneath the flange 4 on one side of the base 1 and has fixed thereon an elongated pulley 15. The pulley 15 is engaged beneath the adjacent flange 4 for retaining this side of the carriage 9 in position in the base 1. A pin 16 in one of the legs 10 is engaged beneath the other flange 4 for retaining the other side of the carriage 9 in position.

25 A flat belt 17 of suitable material is looped or wrapped once around the pulley 15. One end of the belt 17 is anchored, as at 18, to one end of the base 1. The other end of the belt 17 is adjustably anchored to the other end of the base 1 by means including a threaded rod 19. The rod 19 is fixed to the belt 17 and passes slidably through an ear or the like 20 on the base structure 1. A nut 21 is threaded on the rod 19 for tightening or loosening the belt 17. Thus, the frictional grip of the belt 17 on the pulley 15 may be regulated as desired for controlling the pressure of the blade being sharpened on the strop 5.

30 Mounted on the shaft 14 is a blade holder which is designated generally by reference character 22. The holder 22 includes a plate 23 having one end portion rolled in a manner to provide an integral eye or sleeve 24 which is fixed on the shaft 14.

35

Upstanding blade retaining ears 25 are provided on the side edges of the plate 23. Pins 26 and 27 are fixed on the plate 23.

The holder 22 further includes a clamp in the form of a plate 28. The plates 23 and 28 are adapted to receive and clamp therebetween a conventional safety razor blade 29 with the edge 30 thereof which is to be sharpened projecting outwardly from and free of the holder 22 for contact with the strop 5. The blade 29 is positioned on the plate 23 with the pin 27 projecting through said blade. Extending into the plate 28 from one end thereof are slots 31 which slidably receive the headed pins 26. The plate 28 is further provided with a keyhole slot 32 which accommodates the pin 27.

It is thought that the operation of the device will be readily apparent from a consideration of the foregoing. Briefly, the blade 29 to be sharpened is positioned on the plate 23 of the holder 22 with the pin 27 projecting upwardly therethrough. The plate 28 is then slipped into position on the pins 26 and 27 for securing the blade 29 in position in the holder. If desired, the blade may first be honed on the element 13. The operator then grasps the upper portion of the carriage 9 which now functions as a handle and moves said carriage back and forth on the base 1. When this occurs the belt 17 oscillates the shaft 14 as the direction of travel of the carriage 9 is reversed for engaging the blade 29 with the strop 5, the opposite sides of said blade being alternately brought into contact with said strop. The construction and arrangement is such that the holder 22 trails the carriage 9 at all times. As hereinbefore stated, by adjusting the tension of the belt 17 through the medium of the nut 21 on the threaded rod 19, the pressure of the blade being sharpened on the strop 5 may be regulated as desired. Also, the bevel of the edge 30 of the blade 29 may be controlled as desired by loosening or tightening the strop 5.

It is believed that the many advantages of a safety razor blade hone and sharpener constructed in accordance with the present invention will be readily understood, and although a preferred embodiment of the device is as illustrated and de-

scribed, it is to be understood that changes in the details of construction and in the combination and arrangement of parts may be resorted to which will fall within the scope of the invention as claimed.

What is claimed is:

1. A razor blade sharpener comprising an elongated base, substantially channel-shaped in cross section, a strop suspended horizontally in said base, a substantially U-shaped, manually operable carriage slideable in the base and straddling the strop, a shaft journaled transversely in the carriage above the strop, a blade holder mounted on said shaft and below the transverse portion of said carriage, a pulley fixed on the shaft, and a stationary belt mounted on the base and wrapped around the pulley for frictionally oscillating the shaft.

2. A razor blade sharpener of the character described comprising an elongated base of substantially channel-shaped cross section comprising a bottom and upstanding side walls, said base being open at its ends, inturned flanges of angular cross section on the upper edges of the side walls, a flexible strop suspended horizontally under tension in the lower portion of the base, a manually operable, substantially U-shaped carriage slideable in the base and straddling the strop, the bight portion of said substantially U-shaped carriage being arcuate, an abrasive element in said bight portion of the carriage for honing a razor blade, said carriage including legs slideable between the flanges, a shaft journaled between the lower portions of the legs, one end portion of the shaft projecting beneath one of the flanges, a pulley fixed on said one end portion of the shaft and engaged beneath said one flange, a pin on one of the legs engaged beneath the other flange, a holder on the shaft between the legs for receiving a blade and engaging said blade with the strop, a belt mounted longitudinally on the base beneath said one flange and wrapped around the pulley for frictionally oscillating the holder when the carriage is reciprocated on the base, and means for regulating the tension of said belt.

JAMES PERCIVAL ROSS.
